RAILWAY TRAFFIC CONTROLLING
APPARATUS

Paul N. Martin, Penn Township, Allegheny County, Pa., assignor to The Union Switch & Signal Company, Swissvale, Pa., a corporation of Pennsylvania

Application June 10, 1943, Serial No. 490,251

15 Claims. (Cl. 246—63)

My invention relates to railway traffic controlling apparatus, and more particularly to such apparatus using coded energy.

Railway traffic controlling apparatus, such as, for example, cab signal apparatus, using coded alternating track circuit current of commercial frequency may be falsely operated by stray currents from nearby commercial power lines. As a rule, such stray or foreign current flows through the rails in multiple, although the current may not be equal in the two rails. When such foreign current is present, unwanted energy is picked up by the train carried receivers and it becomes necessary for the equipment to distinguish between the usual control current and the foreign current even though the two are of the same frequency. The foreign current flowing partly in each rail, will ordinarily keep the same phase relation for the two portions of the current, or at least will not reverse the phase relation of these two portions at any periodic or code rate even though such current may be varied as to its magnitude by action of the trucks of a train successively spanning the insulated rail joints of adjoining track circuits or some similar condition.

Accordingly, an object of my invention is the provision of improved railway traffic controlling apparatus using coded energy.

Another object of my invention is the provision of improved railway cab signal apparatus that is not subject to false operation by induced current from nearby power lines of the same frequency as the cab signal control current.

Again, an object of my invention is the provision of improved cab signal apparatus that makes use of codes that offer immunity to foreign rail current of the same frequency as the coded track circuit current by which the cab signals are controlled.

Still another feature of my invention is the provision of cab signal apparatus that offers improved broken rail protection.

Other objects, features and advantages of my invention will appear as the specification progresses.

According to my invention, a track section is provided with a series track circuit which includes a source of alternating current connected across the rails at the exit end of the section. This track circuit current may be of commercial frequency, such as 60 cycles per second, and is coded at different codes according to different traffic conditions. Each such code has a predetermined pattern made up of periods that are recurrently

repeated at a predetermined code rate. Furthermore, I provide pole changing means for such trackway apparatus to reverse the phase of the current relatively to the source of supply upon the occurrence of each successive on code period. In other words, the current is coded to have a predetermined code rate and the current pulses of successive on code periods to be of reverse relative polarity. The train is provided with two inductors mounted ahead of the leading pair of wheels with one inductor over each rail for each inductor to receive an electromotive force in response to the track circuit current. The two inductors are alike so that the electromotive forces are of substantially the same magnitude, have a given phase relationship and each is of a code pattern that corresponds to that of the rail current. These two electromotive forces are used to excite a train carried two element two position master relay. The two electromotive forces of the two inductors are first fed into two transformers, each of which is provided with two primary windings and a preselected one of which has two secondary windings. Each inductor and a primary winding of each transformer are connected in series. The two primary windings of the preselected one of the transformers are additive with respect to the electromotive forces received by the inductors due to the track circuit current flowing in the rails in series, and the primary windings of the other transformer are opposed to each other with respect to such received electromotive forces. Conversely, the primary windings of the preselected transformer are opposed and the primary windings of the other transformer are additive in respect to electromotive forces received by the inductors due to foreign current flowing in the rails in multiple. The control electromotive force created in a first one of the two secondary windings of the preselected transformer is applied to a first one of the elements of the master relay through an amplifier to excite that element, and the electromotive force created in the second one of the two secondary windings of the preselected transformer is applied to a second one of the relay elements through a secondary winding of the other transformer and an amplifier to excite that element. These two electromotive forces created in the two secondary windings of the preselected transformer have a given phase relation and the relative polarity of each is reversed each on code period of the rail current due to the phase reversal of the rail current upon the occurrence of each on code period and the master relay would be oper-

ated to one position only unless there is a reversal on the train of the electromotive force applied to one of the relay elements each on code period. I provide the train carried apparatus with phase inverting or pole changing means in the connection of the second relay element and which means is operated each on code period. In this way the electromotive force applied to this second relay element is always of the same relative polarity and the relay is alternately operated to its two positions because of the reversal of the relative polarity of the electromotive force applied to the first relay element due to the phase reversal of the rail current. Consequently, the master relay is operated at a rate corresponding to the code rate of the rail current.

Furthermore, I provide the train carried apparatus with a group of relays controlled jointly by the electromotive force picked up from the rails and by the position of the master relay to synchronize the pole changing of the connection for the second element of the master relay with the on code period of the rail current, and the pole changing of the trackway apparatus and of the train carried apparatus are kept in step.

Such phase reversal of the rail current each on code period together with the special arrangement of the train carried transformer windings substantially removes all possibility of operation of the master relay due to foreign rail current even when such foreign current is of the same frequency as that of the cab signal control current.

I shall describe three forms of apparatus embodying my invention, and shall then point out the novel features thereof in claims.

In the accompanying drawings, Fig. 1 is a diagrammatic view showing one form of trackway and train carried apparatus embodying my invention. Figs. 2 and 3 are diagrammatic views showing two different forms of trackway apparatus each of which may be used with the train carried apparatus of Fig. 1, and each of which also embodies my invention. Fig. 4 is a view showing diagrams of the code patterns of the track circuit current effected by the trackway apparatus of Figs. 1, 2 and 3.

In the different views, like reference characters are used to designate similar parts.

Referring to Fig. 1, the reference characters 1a and 1b designate the track rails of a stretch of railway track and which rails are formed by the usual insulated rail joints with consecutive track sections for a signal system, only the one section D—E and the adjoining ends of the two adjacent sections are shown, however, because these are sufficient to illustrate the invention. Each track section is provided with a track circuit including a current source connected across the rails at the exit end of the section and a track relay connected across the rails at the entrance end of the section. The track relay of one section controls the current source of the section next in the rear, and each track circuit is responsive to traffic conditions in advance of the respective section as well as to traffic conditions of the respective section. Consequently, as the junction location of two sections, a portion of the trackway apparatus is associated with the section next in advance of such location, and a portion is associated with the section next in the rear of such location. The apparatus at all such locations would be substantially alike, and a description of the apparatus at one such location is sufficient for an understanding of all. In Fig.

1, the apparatus at location E is shown complete, while that at location D is only shown in part for the sake of simplicity, and it is to be understood that location D of Fig. 1 and all similar locations are provided with apparatus that is substantially a duplication of that of location E.

Referring to location E of Fig. 1, the immediate current source for the track section D—E is a track transformer TE, the secondary winding 2 of which is connected across the rails of the section at the exit end thereof, and the primary winding 3 of which is supplied with alternating current in a manner to appear shortly. The track relay for section D—E is a direct current relay DTR connected across the rails at location D through a transformer-rectifier unit RQ which rectifies the alternating current supplied to the rails through transformer TE, the unit RQ being shown conventionally since its structure is well-known and forms no part of my invention. Consequently, when section D—E is unoccupied, that is, when a train shown conventionally at TN is not present, track relay DTR is energized and picked up whenever alternating current is supplied to the rails through transformer TE and the relay is deenergized and released whenever such rail current is interrupted. In other words, relay DTR is operated at the code rate of the alternating current supplied to the track circuit.

A track relay ETR for the section next in advance of section D—E is operated by the current supplied to the track circuit of such section in advance in the same manner the track relay DTR is operated by the track circuit current of section D—E.

Operation of track relay ETR at a code rate, such as, for example, 75 or 180 operations per minute, to alternately close its front contact 5 and back contact 6, causes direct current from a source the terminals of which are indicated at B and C, to be alternately supplied to the two portions of winding 7 of a decoding transformer DT, with the result that an electromotive force is induced in winding 8 of transformer DT, the frequency of which electromotive force corresponds to the code rate at which relay ETR is operated. Winding 8 is connected to a relay EH through front contact 9 and back contact 10 of relay ETR, and the electromotive force of winding 8 is rectified for energizing relay EH, relay EH being picked up when relay ETR is operated at either the 75 or 180 code rate.

Two code transmitters or coders 180CT and 75CT are included in the trackway apparatus at location E. The type of such code transmitters is immaterial, and it is sufficient to point out that when current is supplied to an operating winding of a code transmitter, contact members are operated in a cyclic manner at a code rate pre-selected for the transmitter. Front contacts of such contact members are closed during one-half of each operation cycle to form an on code period, and such contacts are open during the other half of each code cycle to form an off code period. As here shown, the operating winding of code transmitter 180CT is supplied with current by an obvious circuit including front contact 11 of relay EH and its contact members 12, 13 and 14 are cyclically operated at the rate of say 180 times per minute. The operating winding of code transmitter 75CT is supplied with current by an obvious circuit including back contact 15 of relay EH and contact members 16, 17 and 18 of this code transmitter are cyclically operated at say 75 times per minute. It is to be under-

stood, of course, that my invention is not limited to these code rates, and other code rates can be used.

When two different code rates, such as 75 and 180 are provided, the code rates would be used to control a wayside signal to different positions, but such way side signal and control means are omitted from the drawing for the sake of simplicity since they form no part of my invention.

Two relays FS and BS are operatively associated with the code transmitters to provide a pole changing means, relays FS and BS being operated at half the code rate of the active code transmitter. Assuming that relay EH is picked up closing front contact 11 to set coder 180CT into operation and relays FS and BS are at the start both released, neither relay is energized during an initial on code period of coder 180CT. At the first off code period current flows from terminal B through front contact 11 of relay EH, coder contact 12-19, back contact 20 of relay BS and winding of relay FS to terminal C, and relay FS is picked up. At the next and first effective on code period, relay FS is retained energized by a stick circuit including its own front contact 23 and coder contact 12-21. Also current flows from terminal B through front contact 11, coder contact 13-22, front contact 26 of relay FS and winding of relay BS to terminal C, and relay BS is picked up. At the next and second off code period relay BS is retained energized by a stick circuit including its own front contact 25 and coder contact 12-19, but relay FS is now without current and is immediately released. At the next and second effective on code period, relay FS remains deenergized, and relay BS is deenergized and released due to the opening of its stick circuit. At the next and third off code period, the above described cyclic operation of relays FS and BS is again initiated. It is to be seen that for the first, third and all odd numbered on code periods of coder 180CT, relay FS is picked up and for the second and all even numbered on code periods relay FS is released. Contact members 16 and 17 of code transmitter 75CT control the circuits for relays FS and BS in the same manner that these circuits are governed by contact members 12 and 13 of coder 180CT, and hence when relay EH is released closing back contact 15 to set coder 75CT into operation, the relays FS and BS are cyclically operated at half the code rate of coder 75CT, relay FS being picked up for the odd numbered on code periods and being released for the even numbered on code periods.

Relay FS is provided with pole changing contacts through which current is supplied to transformer TE from a suitable source of alternating current the terminals of which are indicated at BX and CX, and which source may be of any frequency and may be of the usual commercial frequency of 60 cycles per second. When track relay ETR is released as it will be when the section next in advance of section D-E is occupied, relay EH is released closing back contacts 15 and 27. The closing of back contact 15 brings about operation of coder 75CT, and in turn of relays FS and BS are explained above. During an odd numbered on code period, relay FS is picked up, alternating current flows from terminal BX through front pole changing contact 28 of relay FS, contact 18-29 of coder 75CT, back contact 27 of relay EH, primary winding 3 of track transformer TE and front pole changing

contact 30 of relay FS to terminal CX, and alternating current of a given relative polarity is supplied to the track circuit of section D-E. During each even numbered on code period, the connection is pole changed at back contacts 31 and 32 of relay FS, and the current supplied to the track circuit through transformer TE is of the reverse relative polarity. That is, the circuit is pole changed so as to reverse the phase of the current supplied to the track circuit with respect to the BX-CX source upon the occurrence of each on code period. When the section next in advance of section D-E is unoccupied and relay ETR is operated, relay EH is picked up closing front contacts 11 and 33, the closing of front contact 11 bringing about operation of coder 180CT and of relays FS and BS in the manner already explained. During an odd numbered on code period current flows from terminal BX through front contact 28 of relay FS, coder contact 14-34, front contact 33 of relay EH, primary winding 3 of transformer TE and front contact 30 to terminal CX. During each even numbered on code period, relay FS is released and current of reverse relative polarity is supplied to the primary winding 3 of transformer TE. Hence the track circuit current is now of the 180 code rate and the phase is reversed each on code period. The pattern of such coded current is illustrated by the upper graph of Fig. 4, which will be readily understood by an inspection of the drawings.

As stated hereinbefore, track relay DTR at location D controls the supply of current to the track circuit of the section next in the rear of section D-E, in the same manner that relay ETR controls the supply of current to the track circuit of section D-E.

A train traversing section D-E is indicated conventionally at TN, train TN having mounted thereon cab signal apparatus which is effectively controlled by the coded alternating current supplied to the rails of the section D-E by the trackway apparatus at location E. This train carried apparatus includes two inductors 35 and 36 mounted ahead of the leading pair of wheels above rails 1a and 1b, respectively. These inductors are alike and consequently the electro-motive forces picked up by the inductors due to this coded rail current are of substantially the same magnitude, have a given phase relation and each is of the same code pattern as that of the rail current. These inductors are connected to a first and a second train carried transformer T1 and T2, transformer T1 being provided with two primary windings 37 and 38, and two secondary windings 39 and 40; and transformer T2 being provided with two primary windings 41 and 42 and a secondary winding 43. Inductor 35, primary winding 37 of transformer T1 and primary winding 41 of transformer T2 are connected in series; and inductor 36 is connected in series with primary windings 38 and 42 of transformers T1 and T2, respectively. Primary windings 37 and 38 of transformer T1 are disposed to be additive and windings 41 and 42 of transformer T2 are disposed to oppose each other with respect to the electromotive forces picked up by the inductors in response to the track circuit current. The relative direction of the received electromotive forces is illustrated by arrows placed in the drawings. It is to be seen, therefore, that a control electromotive force is induced in each secondary winding 39 and 40 of transformer T1 but none is induced in secondary

winding 43 of transformer T2 in response to the track circuit current.

A master code following relay MF of the train carried apparatus is excited by the electromotive forces induced in secondary windings 39 and 40, relay MF being a two element two position alternating current relay. Furthermore, relay MF is characterized by its armature once started from a position the armature moves to the opposite position even though the relay in the meantime becomes deenergized, and also by its armature remaining in the position to which it was last moved when the relay is deenergized. A first element 44 of relay MF is connected to secondary winding 39, preferably through an amplifier AM1 of standard construction. A second element 45 of relay MF is connected to secondary winding 40 through a similar amplifier AM2, secondary winding 43 of transformer T2 and contacts of a group of relays A, N and R, as well as contacts of the master relay MF. These amplifier circuits for elements 44 and 45 are arranged to provide the usual phase shift of approximately 90 degrees between the magnetic fluxes set up in the relay MF to operate the relay. To be explicit, a first connection can be traced from the right-hand terminal of secondary winding 40 through wire 46, normal contact 47 of relay MF, back contact 48 of relay R, secondary winding 43 of transformer T2, wire 49, top right-hand input terminal of amplifier AM2 to its lower right-hand input terminal, wire 50, front contacts 51 and 52 of relays A and N, respectively, back contact 53 of relay R, normal contact 54 of relay MF and to the left-hand terminal of secondary winding 40. A second connection can be traced from the right-hand terminal of secondary winding 40 through wire 46, reverse contact 55 of relay MF, back contact 56 of relay N, front contact 57 of relay R, front contact 51 of relay A, wire 50, lower right-hand input terminal of amplifier AM2 to its upper right-hand input terminal, wire 49, secondary winding 43, back contact 58 of relay N, and reverse contact 59 of relay MF to the left-hand terminal of secondary winding 40. It is to be noted that the first traced connection included normal contacts of relay MF and passed from the top to the lower input terminal of amplifier AM2 and through the secondary winding 43 from left to right, whereas the second traced connection included reverse contacts of relay MF and passed from the lower to the top input terminal of the amplifier and through secondary winding 43 from right to left. That is to say, the connection of secondary winding 40 to amplifier AM2 is pole changed by these two circuit connections, such pole changing being effected each operation of relay MF.

The relays A, N and R serve to synchronize the pole changing action of relay MF with the reversal of the phase of the track circuit current. Relay A is connected to the output side of amplifier AM1 preferably in multiple with the element 44 of relay MF, and relay A is energized by a portion of the electromotive force received by the secondary winding 39, with the result that relay A is picked up whenever an electromotive force is received in response to an on code period of the track circuit current and is deenergized and released during each off code period of the track circuit current. The connection of relay A to the output side of amplifier AM1 includes a full wave rectifier 60, back contacts 61 and 62 of relays R and N, respectively, and a resistor

63 which shunts back contacts 61 and 62. The arrangement is such that relay A is picked up only when relays N and R are released and is provided with a release value of current that is substantially as high or higher than the pick-up value of current to assure a quick release of the relay. Relays R and N are in turn governed by relay A according to the position of the master relay MF. With relay A picked up and relay 10 MF at its normal or right-hand position, current flows from terminal B through normal contact 64 of relay MF, front contact 65 of relay A, winding of relay N and back contact 66 of relay R to terminal C. Relay N once picked up is retained energized by a stick circuit independent of relay MF and which stick circuit includes front contact 67 of relay N, front contact 65 of relay A and back contact 66 of relay R. Similarly, when relay A is picked up and relay 20 MF occupies its reverse or left-hand position, relay R is selected by current flowing from terminal B through reverse contact 68 of relay MF, front contact 69 of relay A, back contact 70 of relay N and winding of relay R to terminal C. Relay R is provided with a stick circuit including its own front contact 71, front contact 69 of relay A, and back contact 70 of relay N. The function of relays A, N and R will appear more fully when the operation of the apparatus is described.

A three position cab signal CS is controlled by the master relay MF according to the code rate at which the master relay is operated. Operation of relay MF to alternately close contacts 72 and 73 causes direct current to be alternately supplied to the two portions of a primary winding of a decoding transformer of a decoding unit DU of well-known construction and which is shown conventionally for the sake of simplicity. It is sufficient for this application to point out that operation of relay MF at the 180 code causes decoding unit DU to be energized in a manner that a relay AA is energized to in turn cause a clear lamp 74 of cab signal CS to be illuminated. When relay MF is operated at the 75 code rate unit DU is energized in a manner to cause relay AA to be deenergized and a relay LL to be energized and an approach lamp 76 of signal CS to be illuminated, and when relay MF is inactive then the unit DU is conditioned to cause both relays AA and LL to be deenergized and a slow speed lamp 77 of signal CS to be illuminated.

In describing the operation of the apparatus of Fig. 1, I shall assume that the track section next in advance of section D-E is unoccupied and track relay ETR is operated so that track circuit current coded at the 180 code rate is supplied to the section D-E and corresponding electromotive forces are picked up by inductors 35 and 36 of the train TN causing corresponding electromotive forces to appear in secondary windings 39 and 40 of transformer T1. I shall also assume at first that no foreign current is present. At the start, the electromotive force of secondary winding 39 is amplified and relay A and element 44 of the relay MF are energized thereby. The connection to the element 45 of relay MF is at the start open, and the electromotive force created in secondary winding 40 is ineffective. Picking up of relay A with relay MF occupying its normal position, selects relay N, and with relays A and N picked up and relay R released, the first traced connection for secondary winding 40 is closed causing element 45 of relay MF to be energized. The parts are dis-

posed so that the phase relation of the electromotive forces applied to elements 44 and 45 of relay MF causes the relay to be operated to its reverse position. Such operation of relay MF opens normal contacts 41 and 54 in the connection by which element 45 is excited, but full movement of the armature of relay MF to its reverse position is effected because of the characteristics of the relay. At the end of this on code period, relay A becomes deenergized and immediately releases. At the next on code period the relay A and the element 44 of relay MF are again excited. With relay A picked up, and relay MF at its reverse position, relay R is selected; and with relays A and R picked up and relay N released, the second traced circuit connection for secondary winding 40 is closed and element 45 of the master relay MF is excited. The phase of the rail current of this second on code period is reversed from that of the current of the first on code period and the relative polarity of the electromotive force applied to the first element 44 is reversed but that applied to the second element 45 is the same due to the pole changing of the connection of secondary winding 40 with the result the phase relation of the electromotive forces applied to elements 44 and 45 of relay MF is reversed and the relay is operated to its normal position. It is to be seen therefore that relay MF is operated at the 180 code rate corresponding to that of the rail current, and the cab signal lamp 74 is illuminated. Since the first connection for secondary winding 40 includes a front contact of relay N and a back contact of relay R, and the second connection includes a back contact of relay N and a front contact of relay R, and since neither relay N nor relay R can be picked up unless relay A is energized, it follows that pole changing of the connection of winding 40 can be effected only subsequent to the beginning of an on code period of the rail current.

If the section next in advance of section D-E is occupied and the track circuit for the section D-E is supplied with current of the 75 code rate, the operation of the train carried apparatus is the same as described above except that relay MF is operated at a rate corresponding to the 75 code rate and lamp 76 of signal CS is illuminated. If another train occupies section D-E ahead of train TN to shunt the track circuit current, then master relay MF is inactive and the slow-speed lamp 77 is illuminated.

Electromotive forces picked up by inductors 35 and 36 due to foreign current flowing in the rails of section D-E in multiple and of equal value in each rail will be balanced out at transformer T1 but a corresponding electromotive force will be created in secondary winding 43 of transformer T2 due to the arrangement of the windings of the transformers. The foreign electromotive force of secondary winding 43 will have a component that is in phase or is 180 degrees out of phase with the control electromotive force created in secondary winding 40 of transformer T1 due to the normal track circuit current. If such component is in phase the operation of the master relay MF is not effected because the pole changing of the connection to the relay element 45 causes the relative polarity of the electromotive force applied to element 45 to be always of the same polarity, and the foreign electromotive force only serves to energize this relay element at a higher level. If this component is 180 degrees out of phase with the con-

trol electromotive force and is high enough it would prevent operation of the master relay for one on code period. On the next on code period the reversal of the phase of the control electromotive force will bring the two electromotive forces into phase and operation of the master relay will proceed. The quadrature component of the electromotive force in winding 43 does not produce torque on relay MF because of the proportioning of the 90 degree phase shifting means included in the amplifier circuits referred to hereinbefore.

When the foreign current is unequal in the two rails a resultant electromotive force is created in secondary winding 43 of transformer T2 and applied to the second element 45 of the master relay the same as described above. There is now a resultant foreign electromotive force created in each of the secondary windings 39 and 40 of transformer T1, and if difference between the foreign current in the two rails is large enough such electromotive forces might overcome the control electromotive forces and hold the master relay at one position or the other. Such action would cause the most restrictive cab signal 71 to be displayed. It appears, however, that with the arrangement here provided it should take a relatively high energy level of foreign current to cause non-operation of the master relay.

Foreign currents alone would not operate the master relay. If the foreign current is equal in the two rails, the received electromotive forces are balanced out at transformer T1 and the first element 44 of the relay MF and relay A remain deenergized. If the foreign current is unbalanced, the energy applied to the first relay element 44 does not reverse in phase and would tend to maintain relay A continuously picked up. Even if a variation of the foreign current should occur in some manner, such as, by the train trucks passing or spanning the insulated joints of adjoining sections, the current in the master relay would remain in the same direction and it would not operate more than once because the electromotive force of winding 43, which depends on the sum of the two rail currents, is larger than the electromotive force of winding 40, which depends on the difference between the rail currents.

The apparatus has the advantage of affording improved broken rail protection for the cab signals. When the train approaches a break in the rail, the difference between the high current in the good rail and the low current in the broken rail tends to create an electromotive force in secondary winding 43 of the second transformer T2 and which electromotive force sets up a polarizing action for the relay element 45 that tends to hold relay MF in one position.

Fig. 2 discloses trackway apparatus where alternating current for governing cab signals is superimposed on a coded direct current track circuit. The track circuit for track section D-E of Fig. 2 includes a battery 84 which is connected across the rails to supply direct current for energizing track relay DTR connected to the rails at the entrance end of the section, relay DTR being connected to the rails without the intervening transformer rectifier unit of Fig. 1. It follows therefore that relay DTR will be energized and picked up whenever direct current from battery 84 is supplied to the rails and will be released whenever such current is interrupted and is non-responsive to alternating current supplied across

the rails. Track relay ETR at location E of Fig. 2 is controlled similarly to relay DTR, and relay ETR controls relay EH through decoding transformer DT in the same manner as in Fig. 1. With relay EH picked up closing front contact 11, to bring coder 180CT into operation, a code repeater relay CP for section D—E is operated at the 180 code rate, relay CP being energized by an obvious circuit including contact 78 of coder 180CT and front contact 79 of relay EH. Thus relay CP is energized and picked up during each on code period of coder 180CT and is deenergized and released during each off code period of the coder. When relay ETR is inactive and relay EH released to bring coder 75CT into operation, then the repeater relay CP is operated at the 75 code rate, the circuit for relay CP including contact 85 of coder 75CT and back contact 86 of relay EH. Code repeater relay CP is characterized by having a predetermined transfer period for its contacts. That is, when relay CP is energized and picked up a predetermined interval occurs between the opening of its back contacts 80 and 81 and the closing of the corresponding front contacts 82 and 83. Likewise, when relay CP is deenergized the same predetermined period is required between the opening of front contacts 82 and 83 and the closing of the corresponding back contacts 80 and 81. During the period relay CP is picked up, track battery 84 and secondary winding 2 of transformer TE are connected in series across the rails, one terminal of battery 84 being connected to rail 1b through front contact 82 of relay CP and a resistance 81, and the other terminal of battery 84 being connected to rail 1a through secondary winding 2 and front contact 83 of relay CP. During each period relay CP is released secondary winding 2 is connected across the rails independent of battery 84, the connections being completed at back contacts 80 and 81 of relay CP. Thus, operation of relay CP causes direct current to be supplied to the rails at a code corresponding to the code rate at which relay CP is operated, and also causes alternating current to be supplied to the rails, the alternating current being superimposed on the direct current during the period the direct current flows and being of one relative polarity, and the alternating current being of reverse relative polarity during the off periods of the direct current. Furthermore, a predetermined off period of the alternating current occurs during each transfer period of the contacts of relay CP. The code pattern of the alternating current for the apparatus of Fig. 2 is illustrated by the lower graph of Fig. 4, and will be readily understood by an inspection of that drawing.

Assuming that the train TN of Fig. 1 with its train carried apparatus occupies section D—E of Fig. 2, while the section next in advance is unoccupied and relay CP is operated at the 180 code rate, the alternating current supplied to the rails induces an electromotive force in each of the train inductors and relay MF is operated to its reverse and normal positions in substantially the same manner as described in connection with Fig. 1. During the transfer period of relay CP, that is, during the off period of the coded alternating current, relay A of the train carried apparatus is deenergized and released, with the result that the connection for secondary winding 40 of the train carried transformer T1 is pole changed and relay MF is operated to its normal or reverse positions at the beginning of each on code period of the alternating current. With

such operation of the master relay MF, the decoding unit DU is energized and lamp 74 is illuminated, unit DU of Fig. 2 being proportioned to control indication lamp 74 when relay MF is operated at a rate corresponding to the 180 code rate of the rail current, and to control lamp 76 when relay MF is operated at a rate corresponding to the 75 code rate of the rail current.

Fig. 3 shows trackway apparatus where alternating current for cab signal control is superimposed on coded direct current track circuits using a feed back code for approach control. The code repeater relay CP1 of Fig. 3 is operated by trackway apparatus for the section next in advance of section D—E in the manner that code repeater relay CP of Fig. 2 is operated, and in a similar manner a code repeater relay CP2 of Fig. 3 is operated by the track apparatus of section D—E for controlling the track circuit for the section next in the rear. Furthermore, each repeater relay CP1 and CP2 of Fig. 3 is characterized by a predetermined transfer period for its contacts the same as explained for relay CP of Fig. 2.

It is believed that the apparatus of Fig. 3 can best be understood by a description of its operation. Assuming that repeater relay CP1 is being operated at the 180 code rate and it is energized and picked up to close its front contact 115, direct current flows from battery 88 through front contact 115 to rail 1b, through rail 1b and wire 89 to a winding of track relay DTR1, normal polar contact 90 of a relay DIR to be later described, wire 91, rail 1a, wire 92, top portion of secondary winding 93 of a transformer TE1 and resistor 94 to battery 88. Track relay DTR1 is energized and picked up by this direct current to open its back contact 95 and close its front contact 96. This operation of contacts 95 and 96 causes direct current to be alternately supplied to two portions of primary winding 97 of a decoding transformer TD with the result an electro-motive force is induced in secondary windings 98 and 99 of that transformer. The electro-motive force induced in secondary winding 98 is supplied to a control relay DH through rectifying contacts of relay ETR1, as will be readily understood by an inspection of Fig. 3. The electro-motive force induced in secondary winding 99 is applied to the winding of relay DIR to energize that relay. Relay DIR is a bias polar relay whose armature is biased to the left-hand position as viewed in Fig. 3 when the relay is deenergized and is held in that left-hand position when the relay is energized by current of one polarity and the armature is operated to the right-hand position when the relay is energized by current of the reverse polarity. The connection of secondary winding 99 is such that the electro-motive force induced in secondary winding 99 when relay DTR1 is dropping out is of the polarity that operates relay DIR to its right-hand position. Such operation of relay DIR disconnects the track relay DTR1 and connects battery 100 to the track circuit. Assuming now that during this operation of the relays at location D the repeater relay CP1 is released for an off code period, current flows from battery 100 through wire 89, rail 1b, back contact 101 of relay CP1, wire 102, unit 103, top winding of a relay RC, wire 92, rail 1a, wire 91 and the right-hand polar contact 104 of relay DIR and resistor 105 to battery 100. Relay RC is now operated to close its right-hand contact 106 and complete a simple circuit for supplying

current to an approach slow release relay AR, relay AR being picked up in response to such operation of relay RC. The electromotive force applied to relay DIR shortly dies away and this relay is then operated back to its bias position to close contact 90 and reconnect the track relay DTR1 to the track rails so that on the next on code period of relay CPI the track relay DTR1 is again energized and picked up. The picking up of relay CPI to close its front contact 114 completes a simple circuit for energizing the lower winding of relay RC at a polarity that causes its armature to be operated back to its left-hand position, but the approach relay AR remains picked up during the off period because of its slow release characteristic. The above described operation of the apparatus of Fig. 3 will continue as long as the section D—E is unoccupied, with the result that the control relay DH at location D and the approach relay AR at location E are energized and picked up. Relay DH is used to control repeater relay CP2, relay CP2 being operated by the 180CT coder through front contact 112 of relay DH and being operated by the 75CT coder through back contact 113 of relay DH. Approach relay AR would be used to control any signal desired and in Fig. 3 it is used to control the supply of alternating current to primary winding 108 of transformer TE1, current being supplied to the primary winding through back contact 107 of relay AR.

In the case a train, such as train TN of Fig. 1 with its cab signal apparatus, enters section D—E of Fig. 3, operation of relay CPI continues but the feed back code current from battery 100 is shunted by the train and relay RC remains inactive at its left-hand position, causing approach relay AR to be released. The closing of back contact 107 of relay AR to supply alternating current to primary winding 108 of transformer TE1 causes alternating current to be supplied to the rails by the action of relay CPI, the top half portion of secondary winding 93 of transformer TE1 being connected across the rails through front contact 115 of relay CPI and the lower half portion of secondary winding 93 being connected across the rails through back contact 101 of relay CPI. Hence, each period relay CPI is picked up closing front contact 115, alternating current of one relative polarity is supplied to the rails to flow in the rails in series, and each period relay CPI is released closing back contact 101, alternating current of the reverse relative polarity is supplied across the rails; also there is an off period for such alternating current during the transfer period of the contacts of relay CPI. The unit 103 is a low pass or anti-resonant filter to block flow of alternating current through the top winding of relay RC. A high pass or resonant filter consisting of a condenser 109 and an inductance 110 is interposed in the lead for the lower portion of secondary winding 93 to block the flow of direct current through that portion of the secondary winding. Consequently, when train TN travels the section D—E of Fig. 3 the coded alternating current supplied by the apparatus of Fig. 3 will cause operation of the master relay of the train carried apparatus in the same manner as explained in connection with the apparatus of Fig. 2, the alternating current of Fig. 3 having a code pattern as illustrated by the lower graph of Fig. 4.

It is clear that the train carried apparatus when operated with the trackway apparatus of either Fig. 2 or 3 is immune to false operation by

foreign current flowing in the rails in multiple for the same reasons as described in connection with the trackway apparatus of Fig. 1.

It is to be seen, therefore, that I have provided 5 novel and improved cab signal apparatus that has the advantages of being substantially free from false operation due to foreign current that may be of the same frequency as the frequency of the track circuit current used for controlling the cab signal.

Although I have herein shown and described 10 only three forms of railway traffic controlling apparatus embodying my invention, it is understood that various changes and modifications 15 may be made therein within the scope of the appended claims without departing from the spirit and scope of my invention.

Having thus described my invention, what I claim is:

20 1. In combination, a track section, a source of alternating current connected across the rails of said section to supply current thereto, coding means having contacts interposed in the connection of said current source to the rails and operable at times to code the alternating current to have alternate on and off periods of a preselected rate and a reversal of phase with respect to said current source upon the occurrence of each on period, a train to travel said section provided with receiving means mounted on the train in inductive relation to the rails to receive energy in response to the alternating current thus supplied to the rails, and train carried signal apparatus connected to said receiving means and effectively excited by said received energy due to said code rate and reversal of phase of the rail current.

25 2. In combination, a track section; trackway means including a source of alternating current, a coder and a pole changer; said trackway means connected across the rails of said section to supply such alternating current coded to have recurrent on periods of a preselected code rate and the currents of successive on periods to be of opposite relative polarities with respect to the source of alternating current, a train to travel said section provided with receiving means mounted in inductive relation to the rails to receive energy of a code corresponding to that of the alternating current supplied to the rails, and train carried signal apparatus connected to said receiving means and controlled by said received energy.

30 3. In combination, a track section, trackway apparatus including a source of alternating current connected across the rails of said section to supply thereto an alternating current coded to have recurrent on code periods, a pole changer interposed in said trackway apparatus to reverse the phase of said coded current with respect to said current source upon the occurrence of each on code period, a train to travel said section, receiving means mounted on the train in inductive relation to the rails to receive energy corresponding in code and phase to that of said rail current, a train carried two-element relay, circuit means to connect the two elements of said relay to said receiving means to excite each said relay element due to said received energy, and pole changing means interposed in said circuit means and controlled by the received energy to reverse the connection of a preselected one of said relay elements each on code period of the received energy to operate said relay at a rate corresponding to said recurrent on periods of the rail current.

35 4. In combination, a track section, a source of

alternating current, a coder operable at a pre-selected code rate, a relay having pole changing contacts and controlled by said coder to operate its pole changing contacts at one half said code rate, means including said pole changing contacts and a contact of said coder to connect said current source across the rails of said section to supply alternating current of said code rate and reversed in phase with respect to said current source upon the occurrence of each on code period, a train to travel said section and provided with receiving means mounted in inductive relation to the rails to receive energy corresponding in code rate and phase to the rail current, a train carried two-element relay having each of its two elements connected to said receiving means to excite each said element by said received energy, and said two-element relay provided with pole changing contacts which are included in the connection of a pre-selected one of its elements to said receiving means to operate said two-element relay at said code rate due to said reversal of the phase of the rail current and the pole changing of the connection to said preselected relay element.

5. In combination, a track section, trackway means including a source of alternating current and a coder and a pole changer and connected across the rails of said section to supply thereto an alternating current coded to have alternate on and off periods and a reversal of phase with respect to said current source upon the occurrence of each on period, a train to travel said section and provided with receiving means mounted on the train in inductive relation to the rails to receive energy corresponding in code and phase to that of said rail current, a train carried two-element alternating current relay, a first circuit means to connect a first one of the elements of said relay to said receiving means to energize that element by said received energy, a second circuit means including pole changing contacts of said two-element relay to connect a second one of the elements of said relay to said receiving means to energize said second element by said received energy and operate said relay at said code rate, and train carried relay means connected to said first circuit means to be energized in multiple with said first relay element and having contacts interposed in said second circuit means to synchronize the pole changing of said second relay element with the on periods of said rail current.

6. In combination, a track section, trackway means including a source of alternating current and a coder and a pole changer and connected across the rails of said section to supply to the rails an alternating current coded to have alternate on and off periods and a reversal of phase with respect to said current source upon the occurrence of each on period, a train to travel said section, two inductors mounted on the train one over each rail for each inductor to receive an electromotive force corresponding in code and phase to that of said rail current, a train carried two-element alternating current relay, train carried circuit means including a transformer to connect each element of said relay to said inductors to energize each said element by energy due to said received electromotive forces, train carried pole changing means having contacts interposed in the connection to a preselected one of said relay elements, and another train-carried relay connected to said circuit means to be energized each on code period of

the received electromotive forces to control said pole changing means to cause code operation of said two-element relay due to said phase reversal of said rail current.

- 5 7. In combination, a track section having a normal direction of traffic, trackway means including a source of alternating current and a coder and a pole changer and connected across the rails at the exit end of said section to supply alternating current which flows in the rails in series and which is coded to have recurrent on periods with a reversal of phase with respect to said current source upon the occurrence of each on period, a train to travel said section and having two inductors mounted ahead of the leading pair of wheels of the train with one inductor over each rail for each inductor to receive an electromotive force in response to said rail current, a train carried transformer having two primary windings one connected to each of said inductors and disposed to add their effects with respect to said electromotive forces due to said series rail current, a train carried two-element relay, a first circuit means to connect a first one of the elements of said relay to a first secondary winding of said transformer to excite that element in response to said received electromotive forces, a second circuit means to connect the second one of the elements of said relay to a second secondary winding of said transformer to excite that relay element in response to said received electromotive forces, and train carried pole changing means including contacts of said two-element relay and interposed in said second circuit means to reverse the connection of the second relay element each on period of the received electromotive forces to operate said two-element relay at a code rate corresponding to that of the rail current.
- 40 8. In combination, a track section having a normal direction of traffic; trackway means including a source of alternating current and a coder and connected across the rails at the exit end of said section to supply current which flows in the rails in series and which is coded to have recurrent on periods, a train to travel said section and having two inductors mounted ahead of its leading pair of wheels with one inductor over each rail for each inductor to receive an alternating electromotive force in response to each on period of said coded current, a train carried two-element alternating current relay, train carried means to connect the two elements of said relay to said inductors and including a first and a second transformer, said first transformer having two primary windings and two secondary windings and said second transformer having two primary windings and a secondary winding, each inductor connected to two of said primary windings, one of each of the transformers, one element of said relay connected to one secondary winding of the first transformer and the other element of the relay connected to the other secondary winding of the first transformer in series with the secondary winding of the second transformer, and said two primary windings of the first transformer additive in respect to electromotive force received by said inductors due to current flowing in the rails in series and said two primary windings of the second transformer opposing in respect to such electromotive forces due to current flowing in the rails in series whereby said relay is effectively operated in response to said coded current and false operation of the

relay due to foreign current flowing in the rails in multiple is substantially avoided.

9. In combination, a track section, a code transmitter operable to alternately close front and back contacts at a preselected code rate to form a code having alternate on and off periods, a first and a second relay, said first relay provided with a pick-up circuit including a back contact of the code transmitter and a back contact of the second relay and with a stick circuit including a front contact of the code transmitter and said second relay provided with a pick-up circuit including a front contact of the code transmitter and a front contact of the first relay and with a stick circuit including a back contact of the code transmitter whereby said first relay is picked up for the odd numbered on code periods and is released for the even numbered on code periods, a source of alternating current, means including a contact of said code transmitter and pole changing contacts of said first relay to connect said current source across the rails of said section to supply a track circuit current coded at said preselected code rate and a reversal of phase with respect to said source of alternating current upon the occurrence of each on code period, and a train to travel said section provided with signal apparatus disposed in inductive relation to the rails and effectively responsive to the energy received from said track circuit current due to said code rate of its on periods and said reversal of phase each on period.

10. In combination, a track section, a code repeater relay movable to alternately close front and back contacts and characterized by a predetermined transfer interval in the movement between the front and back contacts, a source of alternating current, a first circuit including a front contact of said code repeater relay to connect said current source across the rails of said section to supply a track circuit current of normal relative polarity, a second circuit including a back contact of said code repeater relay to connect said current source across the rails of said section to supply a track circuit current of reverse relative polarity, means including a code transmitter to operate said code repeater relay at a preselected code rate to code said track circuit current to have alternate on and off periods corresponding to said code rate with each on period equal to the interval said front or said back code repeater relay contact is closed and each off period equal to said transfer interval, a train to travel said section and provided with signal apparatus disposed in inductive relation to the rails to receive energy in response to said track circuit current and effectively operated due to said code rate of the on periods of the track circuit and said reversal of its relative polarity.

11. In combination, a track section, trackway means including a source of alternating current connected across the rails of said section to supply current thereto, coding means having contacts interposed in the connection of said current source to the rails and operable at times to code the alternating current to have alternate on and off periods of a preselected rate and a reversal of phase each on period, a train to travel said section and provided with two inductors one over each rail for each inductor to receive an electromotive force corresponding in code to that of said rail current, a train carried transformer having two primary windings one connected to each of said inductors and two secondary windings, a train carried two-element alternating cur-

rent relay having one element connected to a first one of said secondary windings and its other element connected to a second one of said secondary windings for energizing both said relay elements in response to said received electromotive forces, another train carried relay connected to said first secondary winding to energize such other relay by the electromotive force created in said first secondary winding each on period of the rail current, and circuit means including a front contact of said other relay and normal and reverse contacts of said two-element relay to reverse the connection of said second secondary winding to cause operation of said two-element relay at a rate corresponding to said preselected rate.

12. In combination, a track section, trackway means including a source of alternating current connected across the rails of said section to supply current thereto, coding means having contacts interposed in the connection of said current source to the rails and operable at times to code the alternating current to have alternate on and off periods of a preselected rate and a reversal of phase each on period, a train to travel said section and provided with two inductors one over each rail for each inductor to receive an electromotive force corresponding in code to that of said rail current, a train carried transformer having two primary windings one connected to each of said inductors and two secondary windings, a train carried two-element alternating current relay having one element connected to a first one of said secondary windings and its other element connected to a second one of said secondary windings for energizing both said relay elements in response to said received electromotive forces, another train carried relay connected to said first secondary winding to energize such other relay by the electromotive force created in said first secondary winding each on period of the rail current, and train carried circuit means including contacts controlled in part by said other relay and in part by said two-element relay to pole change the connection of said other relay element to said second secondary winding to reverse the phase of the electromotive force supplied to said other relay element for operating said two-element relay at a rate corresponding to said preselected rate.

13. In combination, a track section having a normal direction of traffic and provided with trackway means connected across the rails at the exit end of the section to supply alternating current that flows in the rails in series, said trackway means including coding means to code such current to have alternate on and off periods and the current pulses of successive on periods to be of reverse relative polarities, a train to travel said section provided with two inductors mounted ahead of the leading pair of wheels with one inductor over each rail for each inductor to receive an electromotive force of the same code as said rail current, a first and a second transformer on said train, each said transformer having a first and a second primary winding, said first transformer having a first and a second secondary winding and said second transformer having a secondary winding; said first primary windings connected in series to a first one of said inductors and said second primary windings connected in series to the second one of said inductors, the first and second primary windings of the first transformer disposed to

add the electromotive forces received by said inductors due to said coded series rail current to create a corresponding electromotive force in each of the first and second secondary windings of the first transformer, said first and second primary winding of said second transformer disposed to subtract the electromotive forces received by said inductors due to said coded series rail current, and a train carried two-element relay having one element connected to the first secondary winding of said first transformer and another element connected to the second secondary winding of the first transformer through the secondary winding of the second transformer and pole changing contacts of the two-element relay to operate such relay in response to said coded rail current and to balance out the energization of the relay due to stray alternating current flowing in the rails in multiple.

14. In combination, a track section having a normal direction of traffic, trackway means including a source of alternating current and a coder and connected across the rails at the exit end of said section to supply to the rails current coded to have alternate on and off periods of a preselected code rate, a train to travel said section and provided with receiving means mounted on the train in inductive relation to said rails to receive an alternating electromotive force in response to each on period of said coded current, a train carried two-element alternating current relay, a first circuit means to couple a first element of said relay to said receiving means to energize that element in response to each pulse of said electromotive force, a second circuit means to couple a second element of said relay to said receiving means to energize that element in response to each pulse of said electromotive force, another relay connected to

said first circuit in multiple with said first relay element to be energized by each pulse of said electromotive force, and contacts of said other relay and said two-element relay interposed in said second circuit means to pole change the connection of said second relay element upon the occurrence of each pulse of said electromotive force to operate said two element relay at said preselected code rate.

- 10 15. In combination, a circuit which is supplied at times with alternating current coded to have alternate on and off periods of a preselected code rate, a two-element alternating current relay, a first circuit means to couple a first element of said relay to said circuit to energize that element in response to each pulse of said coded current, a second circuit means to couple a second element of said relay to said circuit to energize that element in response to each pulse of said coded current; a first, a second and a third relay; means to connect said first relay to said first circuit means to energize said first relay in response to each pulse of said coded current, means including a normal contact of said two-element relay and a front contact of said first relay to energize said second relay, means including a reverse contact of said two-element relay and a front contact of said first relay to energize said third relay, and two alternative circuit paths a first one of which includes a normal contact of said two-element relay and a front contact of said second relay and a second one of which paths includes a reverse contact of said two-element relay and a front contact of said third relay, and said two circuit paths included in said second circuit means to pole change the connection of said second relay element to operate said two-element relay at said code rate in response to said coded current.

PAUL N. MARTIN.
